The ornamental design for a tri-lobe light fixture optic, as shown and described.

DESCRIPTION

FIG. 1 is an isometric view of the tri-lobe light fixture optic; FIG. 2 is a bottom view of the tri-lobe light fixture optic; FIG. 3 is a top view of the tri-lobe light fixture optic; FIG. 4 is a side view of the tri-lobe light fixture optic, an opposing side view of the tri-lobe light fixture optic being a mirror image thereof; and,

FIG. 5 is an end view of the tri-lobe light fixture optic. In FIGS. 1-5, the broken lines indicate portions of the light fixture optic that form no part of the claimed design. In FIGS. 1-4, the broken line symbolic breaks and accompanying bracket indicate that the appearance of the article between the break lines forms no part of the claimed design.
